LIQUID CONGEALING APPARATUS

Jules N. Saler, Springfield, Mass., assignor to Westinghouse Electric Corporation, East Pittsburgh, Pa., a corporation of Pennsylvania

Application August 3, 1937, Serial No. 157,117.

6 Claims. (Cl. 62—108.5)

My invention relates to liquid congealing apparatus and particularly to liquid congealing apparatus of the type used in domestic refrigerators.

It is an object of my invention to provide improved apparatus for forming ice cubes of a proper size for domestic use from which a part or all of the ice cubes may be removed as desired.

It is another object of my invention to provide improved liquid congealing apparatus of the mechanical ejection type wherein some or all of the ice cubes may be removed as desired, and wherein those ice cubes which the user desires to remove are rendered extremely accessible.

It is still a further object of my invention to progressively lift ice cubes from an ice tray so that as many cubes as desired may be easily removed from the ice tray, while the remaining cubes are not disturbed.

It is still another object of my invention to provide mechanism for ejecting ice cubes from ice trays of the type used in domestic refrigerators in such a manner that the ice cubes will be lifted from the tray and will not fall back into the tray when loosened unless the user wishes to replace them.

These and other objects are effected by my invention as will be apparent from the following description and claims taken in connection with the accompanying drawings, forming a part of this application, in which:

Fig. 1 is a top plan view of an ice tray and grid constructed in accordance with my invention;

Fig. 2 is a side elevational view of the ice tray and grid, with portions thereof broken away for the sake of clearness;

Fig. 3 is an enlarged view of a portion of the ice tray and grid showing the grid in its raised position;

Fig. 4 is a detail view of a transverse grid wall member;

Fig. 5 is a sectional view of my improved ice pan and grid member taken on line V—V of Fig. 1; and

Fig. 6 is an enlarged view, partly in section, taken on line VI—VI of Fig. 2, and illustrating in detail the linkage mechanism at the left-hand end of the grid member.

Referring specifically to the drawings for a detailed description of my invention, numeral 11 designates an ice pan, preferably formed of rigid stamped aluminum and provided with a reinforcing lip 12. As shown in Figs. 2 and 3, one end of the ice pan 11 slopes upwardly as shown at

13 and the horizontal sides thereof taper inwardly as shown at 14 in Fig. 1. Only a small amount of ice is, therefore, contained in the left-hand end of the ice pan, which is desirable for reasons which will be hereinafter apparent.

A grid structure, generally indicated at 15 is disposed within the ice pan 11 and forms a plurality of cells 16 which form ice cubes 17, as shown in Fig. 3. The grid structure 15 is formed of a longitudinal vertical wall member 18 and a plurality of transverse wall members 19, the latter being shown in Fig. 4 in detail. Each transverse wall member 19 is provided with two horizontal extensions or lifting members 20 for a purpose hereinafter described. Preferably both the longitudinal wall member 18 and the transverse wall members 19 are formed of rigid stamped aluminum. The longitudinal wall member 18 is provided with a plurality of slots 21, 22, 23, 24, and 25 at the top thereof, and each transverse wall member 19 is provided with a slot 26 at the bottom thereof. The longitudinal and transverse wall members are assembled together by sliding the two together, the slots 21 to 25 of the longitudinal wall members each receiving the top of a transverse wall member and the slots 26 in the transverse wall members receiving the bottom of the longitudinal wall member. The slots 26 in the transverse wall members 19 are sufficiently wide that the transverse wall member is loosely assembled on the longitudinal wall member 18. Likewise the slots 21 to 25 in the longitudinal wall member 18 are of sufficient width that the transverse wall members 19 may be rotated a limited distance about the bottom edge 27 of the slots 21 to 25. The slot 21 in the longitudinal wall member 18 is the widest, as shown in Fig. 2, and the slots decrease in width progressively, the slot 25 at the right-hand end of the longitudinal grid member 18 being the narrowest. The reason for this construction will hereinafter be apparent.

In order to retain the transverse and longitudinal wall members 19 and 18 together, and to rotate the transverse wall members relative to the longitudinal wall member, an operating member 28 formed of an inverted U-shaped channel of aluminum or aluminum alloy, is attached to the top of the grid structure 15 by means of pins 30 and 31 secured to the operating member 28 and movable longitudinally in longitudinally extending slots 32 formed in the longitudinal wall member 18 and receiving the pins 31. The operating member 28 is provided with a plurality of upwardly extending slots 33, 34,

35, 36, and 37 which receive upward extensions 38 formed on each transverse wall member 19. As best shown in Fig. 2, the slot 33 is the narrowest, and the slots 33 to 37 progressively widen, the slot 37 being the widest.

In order to lift the grid structure 15 from the ice tray 11 after ice has been frozen therein, and to move the operating member 29 in a horizontal direction thereafter, a leverage and linkage device generally indicated at 40a is provided and 10 comprises a handle 38a which is pivotally attached at 39 to the left-hand end of the longitudinal wall member 18. A link 41 is pivotally attached to the handle 38a by pivot pin 42 and to the operating member 29 at pivot 43, the pivot 15 43 being provided by the pin 31 at the left-hand end of the grid. A spacer 44 connects the pivots 39 and 42 and positions the handle 38a. The handle 38a is provided with an outward extension 45 which engages the lip 12 of the ice tray 11 when rotated in a counterclockwise direction. The left-hand end of the longitudinal wall member 18 is provided with a depression 46 which receives the pin 42 when the parts are in their normal position, as shown in Fig. 2. The pin 42 20 is, therefore, in a slightly over center position relative to the pivot points 39 and 43.

Operation

After the grid structure 15 has been inserted 30 in the ice tray 11, and the ice cubes 17 have been frozen, it is desirable at times to remove only some of the ice cubes 17 therefrom, while at other times it is desirable to remove all the ice cubes. In either case, the cubes are preferably retained by the apparatus in such a position that the user may readily remove them and place them in glasses or the like, without the necessity of dumping the ice cubes first into the sink or defrosting tray.

The handle 38a is, therefore, rotated to first lift the grid structure 15 along its entire length from the ice tray 11, with the ice cubes 17 still adhering to the grid structure 15. When the handle 38a is rotated, a handle 40 attached to the other end of the ice tray is grasped to hold the ice tray and prevent this end from lifting when the handle 38a is rotated. When the handle 38a is rotated counterclockwise, the extension 45 thereof engages the lip 12 of the ice tray, which acts as a fulcrum, and the grid structure is raised slightly to break the ice cubes away from the ice tray 11. The operating member is not moved horizontally during the time the handle 38a is rotated through its initial arc to lift the grid member because the pin 42 first is raised out of the depression 46 to dead center position, then slightly over dead center position, during which time the pin 42 is moving substantially perpendicularly to the link 41, and the link 41 is, therefore, not moved any appreciable distance horizontally. Since the link 41 is connected by pin 31 to the operating member 29, and the pin 31 is rigidly attached to the operating member 29, further rotation of the handle 38a in a counterclockwise direction as shown 50 in Fig. 3 moves the operating member 29 to the left, the pins 30 and 31 sliding in the slots 32 in the longitudinal wall member 18. The side of the relatively narrow slot 33 in the operating member 29 immediately engages the portion 38 of the leftmost transverse wall member 19, thus moving it in the slot 33 in the longitudinal wall member 18 and rotating it about the pivot point 27. Slight further movement of the handle 38a 55 moves the side of the slot 38 into engagement with

the second transverse wall member from the left and moves it in the slot 34 to impart rotational movement to the said second transverse wall member. The slots 33 to 31 progressively decrease in width because the left-hand transverse wall member must move at all times after the handle 38a is rotated to the position shown in Fig. 3, while the other transverse wall members move progressively less, as they extend from left to right.

When the first transverse wall member 19 is rotated, it breaks the ice cubes out of the two small end cells at the left-hand end of the tray 11 by forcing them to the left at the top thereof and these relatively small cubes will fall into the ice tray 11. The cubes to the right of the transverse walls shown in Fig. 3 are broken from the grid structure 15 because the lifting members 20 are rotated to the position shown in Fig. 3. The lifting member when rotated not only shears the ice cubes 17 from the grid walls, but also retains them in a raised position above the outer edges 20 of the grid, so long as the handle 38a is not moved back to its normal position as shown in Figs. 1 and 2. If it is decided not to remove some ice cubes after they have been broken from the grid, the handle 38a may, therefore, again be disposed in its normal position, and the ice cubes 17 which have not been removed will assume their normal freezing position in the ice pan 11.

As the handle 38a is rotated, therefore, and disregarding the very small cubes at the left-hand end of the ice pan, two, four, or any even number of ice cubes up to the full amount in 35 the ice tray, may be progressively broken from the apparatus by successive rotation of the transverse wall members by the mechanism described, and the cubes which are progressively broken are lifted to positions where they are easily removable from the apparatus. I preferably anodize and then treat the ice contacting surfaces of the apparatus with wax or paraffin, as set forth, for example, in the copending application of W. B. Anderson, Serial No. 73,436, filed April 9, 1936, 40 and assigned to the Westinghouse Electric & Manufacturing Company. This treatment materially facilitates the removal of ice cubes from the apparatus.

It is, therefore, apparent that I have provided improved liquid congealing apparatus from which part or all of the ice cubes therein are progressively moved to an accessible position from which the user may readily remove them, and that the mechanism for effecting this desirable result is 50 inexpensive and uncomplicated in construction.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In liquid congealing apparatus, the combination of an ice tray embodying side walls and a bottom wall, a grid member disposed therein for dividing the ice tray into a plurality of ice cube forming cells, said grid member comprising a longitudinal wall member and a plurality of transverse wall members rotatably attached to said longitudinal wall member, manually operable means for progressively rotating said transverse wall members, and angularly disposed members

attached to the bottoms of said transverse wall members normally disposed parallel to the bottom wall of said ice tray, said angularly disposed members progressively engaging ice cubes and lifting them as said manually operable means rotates progressive transverse wall members so as to free part or all of said ice cubes and raise them to an accessible position.

2. A freezing apparatus for liquids comprising in combination, a tray having a grid structure removably disposed therein, said grid structure including a vertically disposed longitudinal wall and a plurality of walls extending transversely from said longitudinal wall in spaced apart relation along the length thereof and dividing the tray into a plurality of ice cube compartments, said transverse walls being mounted on said longitudinal wall to slide therealong and rotate with respect thereto, and being provided with portions extending into said ice cube compartments, means for elevating said grid structure together with ice cubes adhering thereto relative to the tray, and for moving said transverse walls relative to said longitudinal wall to break the bond between the ice cubes and the grid walls and to elevate the ice cubes relative to said compartments.

3. In a grid for an ice tray, at least one separating plate extending longitudinally of said tray; a plurality of movable separating plates extending transversely of said tray, said longitudinally extending plate and said transversely extending plates providing a plurality of compartments for ice blocks; ice block ejecting fingers on said movable plates, positioned to underlie said ice blocks in said compartments; and means for tilting said movable separating plates about an axis extending transversely across the grid as a whole, to cause said fingers to tilt and push said ice blocks upwardly relative to said grid and said tray.

4. A grid for disposition in a freezing tray comprising, a two-part metal longitudinal partition and a plurality of metal partitions extending transversely to said longitudinal partition in spaced apart relation along the length thereof, said partitions being movably interlocked together to provide a unitary grid structure and forming walls of a plurality of ice block compartments, one part of said two-part longitudinal partition

being movable relative to the other part thereof, means for moving said one part of said two-part longitudinal grid partition relative to the said other part thereof, the interlocking of said transverse grid partitions with said longitudinal partition being such that said transverse partitions are progressively engaged by said one part of the two-part longitudinal partition upon movement thereof relative to its other part and are moved relative to said longitudinal partition to liberate ice blocks from their compartment walls, and means associated with said unitary grid structure constructed and arranged to be successively actuated upon progressively moving said transverse grid partitions for moving a portion of the liberated ice blocks upwardly of the top surface of the grid structure to facilitate harvesting of ice blocks therefrom.

5. A freezing apparatus for liquids comprising in combination, a tray having a grid structure removably disposed therein, said grid structure including a vertically disposed longitudinal wall and a plurality of walls extending transversely from said longitudinal wall in spaced apart relation along the length thereof and dividing the tray into a plurality of ice cube compartments, said transverse walls being mounted on said longitudinal wall to move with respect thereto, and being provided with portions extending into said ice cube compartments, means for elevating said grid structure together with ice cubes thereon relative to the tray, and for moving said transverse walls relative to said longitudinal wall to break the bond between the ice cubes and the grid walls and to elevate the ice cubes relative to said compartments.

6. A removable grid for forming ice cubes in an ice tray including a partition and a plurality of transverse plates movable with respect to said partition, at least certain of said transverse plates having means to support ice cubes, and means for moving said transverse plates and ice supporting means with respect to said partition so as to lift at least certain of said ice cubes to loosen the latter from said partition, said means being so constructed as to lift ice cubes in a predetermined order.

JULES N. SALER.
